UNITED STATES PATENT OFFICE.

RICHARD BEEBE, OF WEST SPRINGFIELD, MASSACHUSETTS.

TUNING ATTACHMENT FOR PIANO-FORTES.

Specification forming part of Letters Patent No. 40,015, dated September 22, 1863.

To all whom it may concern:

Be it known that I, RICHARD BEEBE, of West Springfield, in the county of Hampden and State of Massachusetts, have invented a new Attachment to Piano-Fortes for Facilitating the Tuning of the Same; and I do hereby declare that the following is a full, clear, and exact description of the same, reference being had to the accompanying drawings, forming part of this specification.

The object of my invention is to so far simplify the tuning of the piano-forte as to enable any person capable of tuning unisons and octaves to put the instrument in correct tune; and to this end it consists in the attachment of a monochord directly to the sound-board of the instrument, with the addition of such apparatus as may be necessary for bringing the monochord and the string to be tuned simultaneously under the easy control of the hand, thus obtaining a sufficient volume of sound without the necessity of constructing the monochord with a separate sounding apparatus of its own, after the manner of the guitar and viol, as has been usual.

Figure 1 in the drawings is a plan view of the interior of a square piano-forte, showing the application of my invention, but omitting such parts as are not necessary to illustrate it. Fig. 2 is a transverse vertical section of the monochord and a portion of the sound-board. Fig. 3 is a front view of the principal parts of the monochord and a section of a portion of the sound-board. Fig. 4 is an inverted plan of the movable bridge of the monochord. Fig. 5 is a transverse section of a movable bridge of the monochord. Fig. 6 is an inverted plan of the damper of the monochord.

Similar letters of reference indicate corresponding parts in the several figures.

The monochord-string *a* may be arranged in any part of the instrument which may be most convenient. In a square piano-forte I prefer to arrange it between the front bar or brace of the instrument and the bass strings, which arrangement is clearly shown in Fig. 1. This string *a*, like the ordinary strings, *s s*, of the instrument, is attached at one end by a hitch-pin, *b*, to the plate *P* of the instrument, and at the other end by a tuning-pin, *c*, to the wrest-plank *W*. Under the said string *a* there

is glued or otherwise secured to the sound-board *T* a sonometer or graduated scale, *d*, composed of a straight piece of hard wood of about five-eighths ($\frac{5}{8}$) of an inch high and about one-half ($\frac{1}{2}$) an inch wide, and of a length somewhat greater than half that of the vibrating portion of the string *a*. One end of the sonometer is arranged near the ordinary sound-board bridge, *e*, of the instrument, and near this end there is secured in it a notched stud, *f*, which constitutes a bridge for the monochord-string *a*, and near this stud, on the side nearest to the hitch-pin, there is secured a hook, *g*, which holds the string firmly in the notch of the bridge *f*. The said stud *f* and hook *g* have screw-threads upon their shanks, by which they may be raised and lowered at pleasure. The other end of the string *a*, which is attached to the wrest-plank, rests in a notched metal bridge, *h*, which is fitted into a groove, *j*, in the said plank or iron frame, as the case may be, and secured by a cap-plate, *i*, which is placed across it, and screwed to the plank or frame. This bridge *h* may be so moved in the groove *j* as to increase or diminish the length of the vibrating portion of the string *a*, and must be so adjusted that the note of the piano-forte that shall be in unison with the open monochord and the note that shall at the same time be in unison with the monochord stopped at the twelfth (or octave) division shall form a true octave with each other.

In the upper part or face of the sonometer *d* there are secured a series of short metal pins, *v v*, at distances from the bridge *f* corresponding with the musical divisions of the monochord *a* according to the proposed temperament, the said pins being indicated in Fig. 1 by $\frac{1}{2}$ B C $\frac{1}{2}$ D $\frac{1}{2}$ E F $\frac{1}{2}$ G $\frac{1}{2}$ A, commencing from the bridge *f*. The said pins are intended to serve as stops to the movable bridge *R*, the office of which is to check or stop the vibrations of the monochord precisely at the mathematical musical divisions of the string expressed upon the sonometer. The sonometer has also screwed through it horizontally a series of screws, *k k*, corresponding in number with the said stops *v v*, one a little to the right of each stop *v*, such screws serving the two purposes of holding down the movable bridge *R*.

board of the piano-forte constitutes the sound-board for the monochord, rendering any peculiar or separate sound-board for the monochord unnecessary, substantially as herein described.

2. The combination, with the so-applied monochord, of a movable key, by which it can be

struck simultaneously with any one of the strings by the action of the same hand, substantially as herein set forth.

RICHD. BEEBE.
